(57) **CLAIM**

The ornamental design for a digital video disk (DVD), CD and CD-ROM holder, as shown and described.

DESCRIPTION

FIG. 1 is a perspective view of a digital video disk (DVD), CD and CD-ROM holder showing my new design;

FIG. 2 is a left side elevational view thereof; the right side being a mirror image thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a perspective view thereof shown in an open position;

FIG. 8 is a top plan view of FIG. 7;

FIG. 9 is a front elevational view of FIG. 7;

FIG. 10 is a rear elevational view of FIG. 7;

FIG. 11 is a right side elevational view of FIG. 7;

FIG. 12 is a left side elevational view of FIG. 7;

FIG. 13 is a bottom plan view of FIG. 7; and,

FIG. 14 is a cross-sectional view taken along line 14—14 of FIG. 8.
